UNITED STATES PATENT OFFICE.

EDWIN W. HAMMER, OF EAST ORANGE, NEW JERSEY, ASSIGNOR TO CLINE ELECTRIC MANUFACTURING COMPANY, OF CHICAGO, ILLINOIS, A CORPORATION OF ILLINOIS.

METHOD OF MAKING FLYING PASTERS.

Application filed March 6, 1925. Serial No. 13,429.

To all whom it may concern:

Be it known that I, EDWIN W. HAMMER, a citizen of the United States, and a resident of the city of East Orange, in the county of Essex and State of New Jersey, have invented certain new and useful Improvements in Methods of Making Flying Pasters, of which the following is a specification, reference being had to the accompanying drawings forming part thereof.

In high speed presses, particularly those used in the printing of newspapers, it is desirable that the web of paper supplied to the press shall be handled in such a manner as to minimize stoppages of the press and interruption in the supplying of the paper due to breakage of the web, exhausting of a roll of paper, or other causes. As is well known, the rolls of paper used in such presses each weigh about a ton and the web of paper is supplied to the press at the rate of twelve hundred feet a minute, or thereabouts.

It is the present practice, and has been for many years, to secure continuity of supply of web-paper to the press by making what is known as a flying paster. In other words, when the web is nearly exhausted from the active roll which has been supplying paper to the press, the press is slowed down and the end of the web of a fresh roll, which has had an adhesive applied to it, is attached to the web going to press from the depleted roll and after this adhesion takes place the old web is severed and the new web runs to press which is then brought to full running speed.

The making of such a flying paster has involved the use of a rotatable roll stand and traveling belt therefor, in the general manner described in Stone Patent No. 1,124,673, applied for June 18, 1900, and dated January 12, 1915. The traveling belt of such pattern has been an essential feature of successful printing press equipments, being depended upon to feed the paper to the press and to control the movements of the roll of paper against which it pressed and with which it cooperated. The theory of operation for normal running and for the making of a flying paster is described in the above mentioned Stone patent. I have discovered, however, another method of making a flying paster, making possible the employment of simpler and less expensive appara-

tus than has heretofore been required. The simplified apparatus is set forth in the accompanying drawings in which Fig. 1, shows an end elevation of a roll stand adapted for employment in carrying out my improved method; Fig. 2, is a side elevation of the same as viewed from the right. Fig. 3 is an end view in partial section of a simple form of hand brake for use on the roll stand; Fig. 4, is a side elevation in partial section of such hand brake applied to the roll stand; Fig. 5, is an end view of the roll stand with the flying paster in process of being made, and Fig. 6, another view of the same with the flying paster completed and the new roll serving as the source of paper supply for the press.

Referring particularly to Fig. 1, it will be seen that the roll stand is of the conventional form comprising supporting standards 1, carrying the spiders mounted upon a shaft 2, and having arms 3 adapted to serve as a magazine support for 3 rolls of web-paper, the rotation of each roll being controlled by a suitable brake as indicated at 10. In this figure the web of paper is shown as coming from the nearly depleted roll 4 over the rollers 8 and 9, to the press. In Fig. 2, this roll stand is shown as viewed from the right of Fig. 1, the two rolls 5 and 6 being shown as having the ends of their webs trimmed as shown, with adhesive applied thereto as illustrated at A. In this drawing the position of a hand brake 10 is indicated, located between the duplicate arms of the spider at one end of the roll stand; if desired, a similar hand brake might be applied at the other end also. The preferred construction of the hand brake is illustrated in Figs. 3 and 4, in which the arms 3, 3 are corresponding arms of the duplex spiders at one end of the roll stand, the brake being applied to the spindle 11, designed to cooperate with one end of the heavy roll of paper. Such spindle 11 carries an enlarged hub 11^a, around which passes a brake-band 12, supported at one end from the fixed point 14 and having its other end adjustably controlled through the hand wheel 10, the internal screw threaded shank 15, and the threaded extension 16 secured to the brake-band 12. The fixed support 14 is a bar spanning the gap between the two arms 3, 3, as clearly shown in Fig. 4, being fixedly secured to such arms. In making a flying paster in ac-

cordance with my method, the procedure is as follows: The press is brought to a proper speed and the tension secured by the hand-brake 10 is adjusted to maintain a taut web 5 running from the depleted roll; the operator causes the spider of the roll stand to slowly revolve, advancing the new roll 5 toward the outwardly running web 7 until contact is effected between the new roll 5 10 and the expiring web 7 at a point where, as will be seen, there is no physical backing supplementing the tautness of the web; in anticipation of this advance of the new roll, the operator has turned such roll on its spindle 15 so that when contact is made with the outgoing web 7, there will be sufficient time for the new roll to begin turning before the gummed edge comes in contact with the outgoing web 7; the combined effect of the taut web running to press and the slow advancing of the roll 5 is to bring sufficient pressure upon the roll 5 as to cause such roll to turn on its spindle to bring the gummed end of the new web into contact with the expiring 20 web, adhering thereto and traveling to the press with the expiring web from the old roll 4; this takes place with the old web considerably bulged out, as illustrated in Fig. 5; there being nothing behind the web to serve 25 as a backing for the web; when the new web has adhered to the old web and both webs are running to press, the old web is severed below the roll 5, as at X, and the press may then be brought to full running 30 speed, the new roll 5 thus having taken the place of the depleted roll 4 which may thereupon be removed and a fresh roll substituted for it so as to maintain the supply of spare rolls of paper.

40 It is thus seen that I have discovered a mode of making a flying paster without the use of friction belts or other power driven devices for turning and controlling the active web roll, the web thereof thus being 45 fed to press solely by the pull of the press itself.

I claim as my invention the following:

1. The method of making a flying paster of a fresh roll of web paper to the expiring web from a depleted roll being fed to press

solely by the pull of the press itself comprising the use of a rotatable supporting means for a plurality of rolls and means for rotating the same so as to bring a succession of rolls into operating position, the advancement of a fresh roll into contact with the expiring web at a point where such web has no supplementary backing, the setting up of sufficient tension on the expiring web to cause the new roll to gain its initial rotation and bring its gummed extremity into contact with the expiring web to adhere thereto, followed by the severance of the old web back of the point of adhesion.

2. The method of making a flying paster of a fresh roll of web paper to the expiring web from a depleted roll being fed to press solely by the pull of the press itself, consisting of the use of a rotatable supporting means for a plurality of rolls and means for rotating the same so as to bring a succession of rolls into operating position, imposing a positive braking force upon the depleted roll, advancing the fresh roll into contact with the expiring web at a point where such web has no supplementary backing, to cause the new roll to gain its initial rotation and bring its gummed extremity into contact with the web to adhere thereto, and severing the old web back of the point of adhesion.

3. The method of making a flying paster of a fresh roll of web-paper to the expiring web from a depleted roll being fed to press solely by the pull of the press itself, comprising the use of a rotatable supporting means for a plurality of rolls and means for rotating the same so as to bring a succession of rolls into operating position, the reduction of press-speed and regulation of web-tension to a degree where, upon the advancement of a fresh roll into contact with the expiring web at a point where such web has no supplementary backing, such contact will impart to the new roll an initial rotation, bringing its gummed extremity into contact with the expiring web to adhere thereto, severing the old web back of the point of adhesion and re-accelerating the press.

EDWIN W. HAMMER.
